NOVEL KETALS OF A-RING SUBSTITUTED ESTRONES AND RELATED ESTERS AND ETHERS

Leland L. Smith, Malvern, Pa., assignor to American Home Products Corporation, New York, N.Y., a corporation of Delaware

No Drawing. Filed Aug. 24, 1962, Ser. No. 219,128
2 Claims. (Cl. 260—239.55)

The present invention relates in general to certain new and novel 17-ketals of A-ring substituted estrone and estrogenic steroids, intermediates thereof and methods of preparing the same. The invention also encompasses pharmaceutical compositions containing these compounds.

In particular the invention concerns itself with the preparation and use of a novel series of 17-ketalized estrones and esters and ethers thereof which may be represented by the general structure:

wherein R₁, R₂ and R₃ represent a substituent selected from the group consisting of hydrogen, lower alkyl, and lower alkenyl; R₄ represents a substituent selected from the group consisting of hydrogen, lower alkyl, lower alkenyl, lower aralkyl, lower cycloalkyl and acyl; and X represents a member selected from the group consisting of alkylenedioxyethylene, alkylenedithiomethylene, and alkylenthioxyethylene.

In the above definition the term lower alkyl as employed refers to those alkyl groups having from about 1 to 20 carbon atoms, and, more particularly, to those having less than about 10 carbon atoms. The alkyl group may be normal or branched in structure although the normal chain is generally preferred. Some examples of these alkyl groups would be methyl, ethyl, propyl, butyl, isopropyl, pentyl, octyl, dodecyl and cetyl to name a few of such substituents. The term lower cycloalkyl refers to that substituent wherein the carbon atoms are joined in a carbocyclic ring which is generally a 5 or 6 membered ring but which may contain a smaller or larger number of carbon atoms subject to the practical limits of stability of such structures. Cyclohexyl would be an example of a preferred member of this class of substituents. The term lower aralkyl refers in general to an aromatic ring structure substituted by an alkyl group which may contain from about 1 to 20 carbon atoms. An example of this type of substitution would be benzyl, phenylethyl, phenylisopropyl and the like. By the term acyl as employed herein is intended the mono-, di-, or poly-carboxy acid radical derived from a saturated or unsaturated organic acid by removal of the hydroxyl group. Such radicals as the alkanoyl radicals of corresponding acids such as acetyl, propionyl and butyryl derived from acetic, propionic, and butyric acids and the like would therefore fall within the scope of this class of substituent. Radicals from aryl carboxylic acids, as benzoic acid, are also to be included. By the term lower alkenyl as it is employed herein, it is intended to refer to those unsaturated hydrocarbons containing at least one double bond in the chain such as allyl, vinyl and the like. In the present usage this term embraces all such radicals having less than 20 carbon atoms and preferably less than about 10 carbon atoms.

2

An essential portion of this novel structure is the substitution indicated by X in the 17-position of the steroid molecule. It is intended by the definition of alkylenedioxyethylene as employed to define X that it embrace such ketals containing up to about 10 carbon atoms but preferably not more than about 4 carbon atoms. By the term alkylenedithiomethylene it is intended to include those ketals where one oxygen atom of the structure has been replaced by a sulfur atom. In a corresponding manner the term alkylenedithiomethylene as it is employed herein refers to those ketals wherein both oxygen atoms have been replaced by sulfur atoms.

The novel compounds of the invention may be prepared as illustrated by the following flow diagram:

In the above reaction the known compounds 1-alkyl or alkenyl estrone, 2-alkyl or alkenyl estrone or 4-alkyl or alkenyl estrone generally depicted by the structure (I), wherein the substituted group is shown extending into the A-ring at either of positions 1, 2, or 4, is ketalized at the 17-position by treatment with a suitable ketalizing agent such as ethylene glycol and p-toluenesulfonic acid in an inert solvent such as benzene or the like at temperatures up to the reflux temperature of the solvent employed for from 2 to 24 hours' duration to form the corresponding 17-ketal (II). This structure may be etherified or acylated at the 3-position by any one of a number of conventional methods to obtain the corresponding 1-, 2-, or 4-alkyl or -alkenyl 3-substituted 17-ketalized estrones generally illustrated by (III).

In the above generalized preparation of the compounds of the invention where it is desired to prepare the 17-hemithioketal instead of the 17-alkylenedioxy substituted type, a reagent such as thioethanol may be substituted for the alkylene glycol employed in the ketalizing step.

The compounds of the invention are useful in the field of experimental pharmacology as well as being valuable as intermediates for further steroid synthesis in preparing new steroid compounds. In addition, many of the compounds of the invention have been found to demonstrate high antilipemic properties coupled with low feminizing action. Also, besides having capacity to regulate blood lipids, the compounds are useful for their general hormonal effect, particularly in the female. Therefore many of the compounds would be expected to exhibit utility in those areas where estrogens are employed, such as female hypogonadism, amenorrhea, dysmenorrhea metrorrhagia, ovulation block and contraception, pregnancy maintenance, arteriosclerosis, osteoporosis, menopausal symptoms, infertility, regulation of water balance, functional uterine bleeding, and the like.

The novel compounds of the invention when contemplated for use in pharmaceutical products may be employed alone or in combination if desired with a large number of compatible diluents, carriers and the like to form a pharmaceutical composition capable of ready administration. Such liquid carriers as a mineral or vegetable oil or a lower aliphatic alcohol may be used where injectables are to be prepared. Glycerine or the like may be added where the compounds are to be administered as a syrup. Solid excipients, binders, extenders or carriers such as carboxymethylcellulose, starches, sugars and the like may be employed where tablets or powders are to be used as a means of administration. The dosage of the compounds will vary with potency desired and the severity of the ailment, but in general can vary from about 0.5 to 100 mg./kilo of body weight per day, depending upon the factors in the case involved.

In the preparation of the 17-ketals of this invention as illustrated above, only one of a plurality of possible methods of ketalization has been disclosed. It should be understood that within the general framework of the invention other alternate means of ketal formation may be employed if desired. For instance, the process of 17-ketalization to form these novel compounds may be carried out by an exchange reaction which is known as exchange ketalization. In this method the 17-ketone to be ketalized is contacted with the ketal of another carbonyl compound such as the ethylene ketal of acetone, methyl-ethylketone, mesityl oxide or the like in the presence of an acidic catalyst to effect a transfer of the ketal function from the latter compound to the former one. This reaction may be conducted either in the presence or absence of heating as specific conditions dictate. In any event one is thus able to obtain the 17-ketals of the invention.

It should further be noted that the present invention also comprehends the preparation of so-called "open chain" 17-ketals wherein the carbon atoms attached to the oxygen or sulfur atoms are not in fact joined together. However, the preparation of compounds such as these will become clear to those skilled in the art after consideration of the foregoing disclosure. In general the reaction is conducted at temperatures up to the reflux temperature of the solvent employed. It will vary somewhat therefore with the use of benzene, xylene and the like solvents in the reaction. The time of the ketalization, i.e., reflux, will vary from about 2 to 24 hours' duration on an average.

The invention will be further illustrated by the several examples of preparation of selected members of the series which follow. It is, of course, to be understood that these examples are set forth purely by way of illustration and are not intended to limit the scope of the invention in any manner. For a legal definition of the proper scope of the invention, attention may only be directed to the several appended claims.

EXAMPLE 1

17,17-ethylenedioxy-1-methylestra-1,3,5(10)-trien-3-ol

Reflux overnight a mixture of 970 mg. of 1-methyl-estrone [C. Djerassi et al., J. Am. Chem. Soc., 72, 4540 (1950)], 150 mg. of p-toluenesulfonic acid, 100 ml. of benzene, and 10 ml. of ethylene glycol with removal of water via a Dean-Stark apparatus. Then wash the cooled mixture with saturated sodium bicarbonate solution and water, and dry over anhydrous magnesium sulfate. After evaporating the benzene under vacuum, crystallize the solid residue from ether-ethyl acetate-hexane to obtain 730 mg. of product, M.P. 170-172°. Concentration of the mother liquors will afford two further crops of product, 185 mg. of 95 mg., identified as product by their infrared spectra. Recrystallize the main crop to obtain the analytical sample, M.P. 173-175°; $[\alpha]_D +103^\circ$; λ_{max} 281-289 μm (ϵ 2,150), 225 μm (ϵ 8,700, shoulder); $\lambda_{\text{max}}^{\text{KBr}}$ 2.99 μ , 6.41 μ , 6.55 μ , etc.

Analysis.—Calcd. for $C_{21}H_{28}O_3$: C, 76.79; H, 8.59. C, 76.95; H, 8.45.

Thin-layer chromatography using silica gel chromatoplates developed with hexane-ethyl acetate (4:1) will show one component at R_F 0.12 [1-methylestrone at R_F 0.07]; using hexane-ethyl acetate (1:1), R_F 0.70 [1-methylestrone at R_F 0.59].

EXAMPLE 2

17,17-ethylenedioxy-2-methylestra-1,3,5(10)-trien-3-ol

Reflux a mixture of 1.0 g. of 2-methylestrone [Iriarte and Ringold, Tetrahedron, 3, 28 (1958)], 150 mg. of p-toluenesulfonic acid, 100 ml. of benzene and 10 ml. of ethylene glycol for 24 hours with continuous removal of water. Cool the mixture, and wash with aqueous sodium bicarbonate solution. Wash the benzene layer with water, dry over anhydrous magnesium sulfate, and evaporate under vacuum. Dissolve the solids thus obtained in ethyl acetate and concentrate slightly, adding petroleum ether to cause cloudiness. Leave standing for several hours, then filter and dry the precipitated product to obtain the product of this example.

EXAMPLE 3

17,17-ethylenedioxy-2-propylestra-1,3,5-(10)-trien-3-ol

Reflux for 18 hours a solution of 500 mg. of 2-propyl-estrone [Patton, J. Org. Chem., 27, 910 (1962); Holton, J. Org. Chem., 27, 357 (1962)], and 75 mg. of p-toluenesulfonic acid in 75 ml. of benzene containing 5 ml. of ethylene glycol with continuous removal of water. Cool and wash with aqueous sodium bicarbonate solution. Wash the benzene layer with water, dry over anhydrous magnesium sulfate, and concentrate to a small volume. After chilling, the product precipitates, and can be recovered by filtration. For purification dissolve the solids in hot acetone, concentrate somewhat, and add hexane to cause precipitation of product. After several hours filter and dry the crystalline product to obtain the product of this example.

EXAMPLE 4

7,17-ethylenedioxy-4-propylestra-1,3,5(10)-trien-3-ol

Heat together at the reflux for 12 hours, with continuous removal of water, 1.0 g. of 4-propylestrone [Holton, J. Org. Chem., 27, 357 (1962); Patton, J. Org. Chem., 27, 1910 (1962)], 100 mg. of p-toluenesulfonic acid, 100 ml. of dry benzene, and 10 ml. of ethylene glycol. Cool the mixture, and apply aqueous sodium bicarbonate and water wash. Then dry the benzene solution of product over anhydrous magnesium sulfate and evaporate under vacuum. Crystallize the solid residue from methanol and from acetone-hexane mixtures to obtain the product of this example.

EXAMPLE 5

2-allyl-17,17-ethylenedioxyestra-1,3,5(10)-trien-3-ol

In the same manner as described in Example 1, 1.0 g. of 2-allylestrone [Patton, J. Org. Chem., 27, 910 (1962); Holton, J. Org. Chem., 27, 357 (1962)] may be converted to the 17-ethylene ketal which is the product of this example.

EXAMPLE 6

4-allyl-17,17-ethylenedioxyestra-1,3,5(10)-trien-3-ol

In the same manner as described in Example 1, 4 allylestrone [Patton, J. Org. Chem., 27, 910 (1962); Holton, J. Org. Chem., 27, 357 (1962)] may be converted to the 17-ethylene ketal which is the product of this example.

70

EXAMPLE 7

17,17-ethylenedioxy-2-[α -methylallyl]estra-1,3,5(10)-trien-3-ol

One gram of 2-[α -methylallyl]estrone [Patton, J. Org. Chem., 27, 910 (1962)] may be treated with ethylene

glycol in the same way as described in Example 1 in order to obtain the above-named product.

EXAMPLE 8

3-acetoxy-17,17-ethylenedioxy-1-methylestra-1,3,5(10)-triene

Dissolve 100 mg. of 1-methylestrone 17-ethylene ketal in 10 ml. of dry pyridine, and add 3 ml. of acetic anhydride. Leave standing at room temperature for 24 hours, then remove solvents under vacuum. Dissolve the residue thus obtained in acetone, concentrate under vacuum slightly, and add hexane. Leave standing for several hours, then filter the crystalline product of this example.

EXAMPLE 9

3-benzyloxy-17,17-ethylenedioxy-1-methylestra-1,3,5(10)-triene

Dissolve 300 mg. of 1-methylestrone 17-ethylene ketal in 25 ml. of 3% potassium hydroxide solution, and cool to 0°. Add 3 ml. of benzoyl chloride with good stirring; as the benzoate forms it will be precipitated from solution. Leave standing for 30 minutes, then filter and dry the pure benzoate to obtain the product of this example.

EXAMPLE 10

17,17-ethylenedioxy-3-methoxy-1-methylestra-1,3,5(10)-triene

Treat a solution of 1.5 g. of 1-methylestrone 17-ethylene ketal in 250 ml. of boiling methanol and 500 ml. of 10% aqueous sodium hydroxide solution dropwise with 80 ml. of dimethylsulfate. Adjust the addition rate to last for 20 minutes. Then boil the mixture for 30 minutes, and add 170 ml. of 40% sodium hydroxide solution, followed by dropwise addition of an additional 80 ml. of dimethylsulfate added over 20 minutes. Boil the mixture for one hour, cool, and dilute with 300 ml. of water. After cooling further, filter and dry the precipitated product to obtain the product of this example.

EXAMPLE 11

3-ethoxy-17,17-ethylenedioxy-1-methylestra-1,3,5(10)-triene

Treat a solution of 1.0 g. of 1-methylestrone 17-ethylene ketal in 50 ml. of ethanol with 5 ml. of ethyl bromide and 350 mg. of sodium hydroxide. Reflux the mixture for 20 hours, then evaporate the solvents under vacuum. Dissolve the residue in carbon tetrachloride, and wash the carbon tetrachloride solution with 5% sodium hydroxide solution and then with water. Evaporate the washed carbon tetrachloride solution and crystallize the residue obtained from methanol to obtain the product of this example.

EXAMPLE 12

3-allyloxy-17,17-ethylenedioxy-1-methylestra-1,3,5(10)-triene

Reflux a mixture of 500 mg. of 1-methylestrone 17-ethylene ketal, 15 ml. of ethanol, 2 ml. of allyl bromide, and 140 mg. of sodium hydroxide for 18 hours. Remove the solvents under vacuum, and take up the residue in carbon tetrachloride. Wash the carbon tetrachloride solution with 5% sodium hydroxide solution and with water, and then dry and evaporate under vacuum. Recrystallize the solids thus obtained from methanol to obtain the product of this example.

EXAMPLE 13

3-cyclopentyloxy-17,17-ethylenedioxy-1-methylestra-1,3,5(10)-triene

Reflux a mixture of 1.0 g. of 1-methylestrone 17-ethylene ketal, 30 ml. of ethanol, 10 ml. of cyclopentyl bromide, and 750 mg. of sodium hydroxide for 24 hours. Remove the solvent under vacuum, and dissolve the resi-

due in carbon tetrachloride. Wash the carbon tetrachloride solution with 5% sodium hydroxide solution and with water, and finally evaporate under vacuum. Recrystallize the solid residue thus obtained from methanol to obtain the purified 3-cyclopentyloxy-17,17-ethylenedioxy-1-methylestra-1,3,5(10)-triene of this example.

EXAMPLE 14

3-benzyloxy-17,17-ethylenedioxy-1-methylestra-1,3,5(10)-triene

Reflux for 18 hours 1.0 g. of 1-methylestrone 17-ethylene ketal, 50 ml. of ethanol, 5 ml. of benzyl bromide, and 350 mg. of sodium hydroxide. Then remove the solvent under vacuum and dissolve the solids in carbon tetrachloride. Wash the carbon tetrachloride solution with 5% sodium hydroxide solution and with water. Then evaporate the solution and recrystallize the solids thus obtained from acetone to obtain the product of this example.

EXAMPLE 15

1-methyl-17,17-trimethylenedioxyestra-1,3,5(10)-trien-3-ol

Treat a solution of 1.0 g. of 1-methylestrone in 150 ml. of benzene with 60 mg. of p-toluenesulfonic acid and 10 ml. of 1,3-propanediol, and reflux the mixture for 18 hours. Wash the cooled mixture with saturated sodium bicarbonate solution and with water, after which time dry the benzene layer and evaporate under vacuum. Dissolve the solids thus obtained in ethyl acetate, concentrate slightly, and add hexane to cause a haze. The mixture will deposit the product as a crystalline mass, which can be recovered by filtration to form the product of this example.

EXAMPLE 16

17,17-ethylenethioxy-1-methylestra-1,3,5(10)-trien-3-ol

Reflux a solution containing 500 mg. of 1-methylestrone and 30 mg. of p-toluenesulfonic acid in 75 ml. of benzene containing 2 ml. of 2-mercaptoethanol for 6 hours, with continuous removal of water via a Dean-Stark apparatus. Cool the mixture, and wash with saturated sodium bicarbonate solution and then with water. Evaporate the dried benzene solution under vacuum. Crystallize the solids thus obtained from methanol to obtain the pure 17,17-ethylenethioxy-1-methylestra-1,3,5(10)-trien-3-ol which is the product of this example.

EXAMPLE 17

17,17-ethylenedithio-2-methylestra-1,3,5(10)-trien-3-ol

Cool a mixture of 1.0 g. of 2-methylestrone, 5 ml. of ethanedithiol and 25 ml. of chloroform to 5°, and bubble anhydrous hydrogen chloride through the solution for three hours. Then remove the solvent under vacuum, and take up the residue in warm acetone, concentrate slightly, and cool. The pure product of this example will be deposited.

I claim:

1. 17,17-ethylenedioxy-1-methylestra-1,3,5(10)-trien-3-ol.
2. 1-methyl-17,17-trimethylenedioxyestra-1,3,5(10)-trien-3-ol.
